CONTACT SWITCH ASSEMBLY FOR
BAGGING MACHINES

James Dusin and Louis J. Negrilla, Chicago, Ill.,
assignors to Jewel Tea Co., Inc., Barrington,
Ill., a corporation of New York

Application July 7, 1950, Serial No. 172,561

4 Claims. (Cl. 112—11)

1

The present invention relates to a conveyor assembly, and more particularly to a conveyor assembly used in transporting bagged articles from a station where the bag containers are filled to a closing station where the filled bag is closed as by means of stitching, sealing and the like.

In large scale bagging operations, as for example in the bagging of weighed quantities of vegetables, fruits, sugar, flour, and the like, a conveyor system is employed to transport the material in its bag containers from the point at which the loader fills the bag with a measured quantity of material, and into a machine which is arranged to seal the container as by stitching the opposed edges of the container together.

The placing of the bagged articles upon the conveyor system is usually quite irregular or spasmodic, so that the operation of the securing means cannot be timed mechanically for cyclic operation. It is undesirable to keep the stitching machine in continuous operation not only due to the power which is lost by having such machines run idle, but also because the machines are quite noisy.

With the foregoing in mind, an object of the present invention is to provide a conveyor and sealing system for packaging preweighed articles.

Another object of the present invention is to provide a conveyor and sewing machine system in which the sewing machine is energized in relation to the passage of articles at varying time intervals along the conveyor system.

Another object of the present invention is to provide a switch assembly for intermittently energizing a drive motor associated with a sealing mechanism for closing paper or fabric bags, and the like.

Still another object of the present invention is to provide a novel type of switch assembly whose adjuncts cooperate with a bagged article being transported along a conveyor system to intermittently operate a sewing machine as the bagged article is fed thereto.

In the present invention, we have provided a novel type of conveyor system in which the article is transported between guide means which close the open end of the bag by bringing the opposed sides of the bag together prior to introduction into a sewing machine. The energization of the sewing machine is controlled by the rate of passage of the articles themselves, so that the machine is operated only as the articles are being fed thereto and deenergized after passage of the articles through the machine.

2

The present invention will be more completely described in connection with the attached sheets of drawings, in which:

5 Figure 1 is a plan view of a conveyor and sewing machine assembly employing the principles of the present invention;

Figure 2 is a view in elevation of the interior of the switch housing which controls the operation of the sewing machine;

10 Figure 3 is a side view, with parts in elevation, of the switch housing and switch assembly;

Figure 4 is a cross-sectional view taken substantially along the line IV—IV of Figure 2, and illustrating the condition when the switch operating mechanism is in contact with the switch, thereby deenergizing the sewing machine;

15 Figure 5 is a view similar to Figure 4 but illustrates the condition where the switch is actuated to energize the drive motor for the sewing machine;

Figure 6 is a plan view of a shoe assembly used in conjunction with the switch shown in Figures 2—5; and

20 Figure 7 is a cross-sectional view taken substantially along the line VII—VII of Fig. 6.

As shown on the drawings:

The conveyor assembly of the present invention consists in general of a frame assembly 10 having a horizontal table 11 over which a conveyor belt or band 12 is arranged to pass. At spaced points along the table 11, there are provided a plurality of vertical channel members 13 which support a pair of spaced parallel horizontal guide rails 14 above the belt 12.

25 Also secured to the table 11 are a pair of brackets 15 and 16 for rotatably supporting a pair of pulleys 17 and 18.

30 A plurality of vertical frame members 20, 21, 22 and 23 are also rigidly secured to the frame assembly 10, the vertical frame members 20 and 21 each carrying a pair of support arms 24. Similarly, the vertical frame members 22 and 23 carry support arms 25.

35 Each of the support arms 24 and 25 carries a pulley 30 which acts as idler pulleys in a guide belt system. A guide belt 31 is trained about the pulleys at one side of the assembly, and a second guide belt 32 is trained about the opposite set of pulleys. The guide pulleys 31 and 32 may be driven by means of the drive pulleys 17 and 18 which are suitably driven by a motor (not shown) on each of the brackets 15 and 16.

40 The drive pulleys 17 and 18 are driven in opposite directions, so that the guide belts 31 and 32 are driven at the speed of and in the direc-

tion of the conveyor belt 12 in the region where the guide belt contacts the bagged articles. As illustrated in Figure 1, the direction of the conveyor belt 12 is from left to right, so that the guide belts 31 and 32 also move to the right in the region where the guide belts 31 and 32 engage the articles to be packaged.

In Figure 1, there is illustrated a plurality of bags 35 each filled with a predetermined weight of potatoes 36. Each of the bags 35 is placed on the conveyor so that the folded opposed sides 37 of each bag are turned inwardly along their old lines to facilitate folding the opposed front and rear surfaces 38 and 39 of the bag together.

As the bags 35 are conveyed by the conveyor belt 12, they are engaged by the moving guide belts 31 and 32 as illustrated in Figure 1 to bring the opposed flat front and rear surfaces 38 and 39 of the bags together, to facilitate the sewing of these two surfaces together. In the drawings, there is illustrated the condition where one of the bags 35 is partially engaged by the drive belts 31 and 32, while the bag at the immediate right of the aforementioned bag is being conveyed toward a stitching machine 40 with its front and rear surfaces 38 and 39 held in close proximity to each other.

After the tops of the bags are folded together, the conveyor feeds the closed bags into the stitching machine 40 containing a stitching mechanism (not shown) which rapidly sews together the tops of the surfaces 38 and 39 of the bag. The stitching machine 40 is provided with a curved guide portion 41 which functions further to squeeze the front and rear bag surfaces 38 and 39 together prior to their engagement with the stitching mechanism.

The energization of the drive motor M included in the stitching machine 40 is controlled in accordance with the present invention by means of a switch assembly designated generally at 42 and mounted on a sub-frame 11a of the framework 11. The switch assembly 42 includes a housing 43 journailling a central cam shaft 44 therein. The bottom end of the cam shaft 44 projects beneath the bottom of the housing and a flexible spring arm 45 is pinned to this end. This spring arm when deflected will develop operating torque for quick rotation of the shaft 44. The extreme end of the arm carries a shoe 46 in the path of the bags exiting from the guide belts 32 and 33 at a level below the belts and are engaged by the expanded portions of the bags just below their closed tops. The construction of the shoe is more clearly shown in Figs. 6 and 7. As will be seen from those figures, the shoe 46 consists of a relatively thin metal strip having a beveled edge portion 47 on one surface thereof, and a bent over portion 48 which is secured to the flexible arm 45 as by means of bolts 49. An arcuate portion 50 joins the bent over portion 48 with the flat surface 51 for added strength.

The details of the switch assembly are best illustrated in Figures 2 through 5. As shown in the drawings, the cam shaft has a reduced diameter end portion 44a rotatably held within a suitable aperture in the top of the housing 43. A support collar 70 secured to the cam shaft 44 rides on the bottom wall of the housing and prevents axial displacement of the cam shaft 44 within the housing 43.

The cam shaft 44 carries a pair of superimposed cams or dogs 53 and 54 in the housing 43. Also included within the housing 43 is a normally closed switch 55 having terminals 56 and 57 to

which are connected a pair of leads 58 and 59 in an energizing circuit C. As shown in Fig. 1 the switch is inserted in series with one of the energizing leads to the drive motor M of the stitching machine 40 to control energization of the drive motor (as through a solenoid, not shown) as will be hereinafter explained.

The uppermost dog 53 operates as a switch actuating member through contact with an operating button 60 of the switch 55. The switch 55 may conveniently be a quick acting switch of the type commercially known as a microswitch. The upper portion of the dog 53 contacts the operating button 60 in the position illustrated in Figure 4, when the shoe 46 is out of contact with a bag 35. Under these conditions, the drive motor to the sewing machine 40 is deenergized, since the switch 55 is a normally closed switch and opens upon pressing the operating button 60.

In order to decrease the mass of the operating dog 53, one surface thereof may be beveled as at 62 (Figs. 4 and 5).

The lower dog 54 engages a stop member consisting of a rubber cushion 64 on a threaded shank 65, the shank 65 being threaded through a wall of the housing 43 and held rigidly in position by means of a nut 66. Through this arrangement, the position of the rubber cushion 64 may be adjusted as desired to afford more or less bias upon the dog 54 for holding the dog 53 against the switch button 60.

Operation

In the off condition, that is, when no bag 35 is in contact with the shoe 46, the switch operating dog 53 is urged against the operating button 60, thus opening the switch 55 and holding the drive motor to the stitching machine deenergized. The assembly is kept in this condition by the slight pressure exerted by the rubber cushion 64 against the dog 54.

The shoe 46 is disposed in a plane slightly above the plane of the conveyor belt 12, and at such a level that it will conveniently contact the filled or expanded portion of a bag 35 as the bag is being conveyed through the assembly. As the bag 35 is moved into a shoe-engaging position, the expanded or filled portion of the bag first contacts the beveled edge portion 47 of the shoe 46. Since the arm 45 carrying the shoe 46 is a resilient spring member, the shoe can shift to accommodate bag irregularities and ride over the surface of the bag 35 so that the speed of the bag 35 along the conveyor belt 12 is not impaired. As the bag 35 continues to travel along the conveyor, the shoe 46 will be shifted to deflect the spring arm 45 to the position shown in dotted outline in Fig. 1. In this position, the bag has its end surfaces 38 and 39 guided to the sewing machine 40 by a guide rail 41. The displacement of the shoe 46 into this position is sufficient to build up in the deflected arm 45 an operating torque which quickly rotates the cam shaft 44 in a counterclockwise direction, pressing the dog 54 against the bumper 64, and causing the switch-operating dog 53 to release its pressure against the operating button 60 of the switch 55. As this occurs, the switch is closed, thus energizing the circuit C to the drive motor of the sewing machine 40. The length of the shoe 46 is sufficient so that it remains in contact with the bags until the stitching operation is completed, and as the bag 35 travels beyond the length of the shoe 46, the resiliency in the flexible arm 45, together with the bias of the rubber cushion 64

against the dog 54 rotates the cam shaft 44 in a clockwise direction. This represents a return to the off condition illustrated by the solid lines of Figure 1. In this position, as illustrated in Figure 4, the operating button 60 is re-engaged by the switch operating dog 53 so that the energizing circuit to the drive motor of the sewing machine 40 is again opened. The circuit will be re-energized when the next bag 35 engages the shoe 46 as previously described. From this arrangement, it will be seen that the sewing machine 40 is operated only when a bag 35 has been conveyed to the machine.

From the foregoing, it will be appreciated that we have herein provided a useful and practical conveyor system for use in conveying and securing bagged articles. The sewing machine used to close the open end of the bag is operated only when needed, and the rate of operation is made dependent upon the rate at which the bags are being fed along the conveyor system, resulting in a substantial saving in the power required to operate the sewing machine. The switch assembly of the present invention is mechanically rugged, and not subject to the mechanical failures ordinarily appearing in the more complex devices used for similar purposes.

It will be understood that modifications and variations may be effected without departing from the scope of the novel concepts of the present invention.

We claim as our invention:

1. In a system for conveying open topped, filled containers to a stitching means, including a frame, a conveyor belt movable along said frame, guide belts carried by said frame for closing the open tops of the containers, and electrically operated stitching means receiving said containers from one end of said conveyor belt, a switch housing carried by the frame, a switch in said housing electrically connected to the energizing circuit of the stitching means, switch operating means including a pivotal arm having one end extending into said switch housing for operating said switch, a flexible spring contact associated with said arm and having an inflexible contact element arranged to contact the container on said conveyor belt prior to passage of the container into the stitching means, and an adjustable resilient stop means urging said switch operating means into switch-opening position to hold said switch open until said switch operating means is displaced into switch closing position against said resilient stop by contact of said contact element with a container.

2. In a system for conveying open topped, filled containers to a stitching means, including a frame, a conveyor belt movable along said frame, guide belts carried by said frame for closing the open tops of the containers, and electrically operated means for securing said tops after contact with the guide belts, a switch housing carried by

said frame, a switch in said housing electrically connected to the energizing circuit for the stitching means, pivotal means associated with said housing and arranged to operate said switch, said pivotal means including a flexible spring arm and a relatively inflexible contact member carried by said spring arm and extending along said conveyor track between said guide belts and said stitching means to contact containers during passage of the same into the stitching means to thereby operate said stitching means, and resilient stop means in said housing urging said pivotal means against said switch into switch opening position.

15 3. In a system for conveying open topped, filled containers to a stitching means including a frame, a conveyor movable along said frame, guide means for bringing the opposed ends of an open-topped container together, and electrically operated stitching means for stitching together said opposed ends, a switch housing carried by said frame, a normally closed switch electrically connected to the energizing circuit of the stitching means, a switch operating member pivotally mounted within said housing, a flexible spring arm associated with said switch operating member, a relatively inflexible shoe carried by said flexible arm and arranged to extend into the path of containers on said conveyor immediately prior to said stitching means, whereby the switch will be operated to operate the stitching means upon contact of said shoe with a filled container on said conveyor, and a resilient stop member adjustably secured within said housing urging said member into switch opening position.

35 4. A switch actuator for a biased switch comprising a rockably mounted shaft, first and second superimposed dogs on the shaft, said first dog confronting the biased switch, an adjustable resilient bumper acting on the second dog to hold the first dog against the switch, and a deflectable spring arm secured on said shaft effective to build up shaft operating torque when deflected for quickly rocking the shaft to cause the second dog to load the bumper and to move the first dog away from the switch.
